UNITED STATES PATENT OFFICE.

JULIA K. McDANIEL, OF WASHINGTON, DISTRICT OF COLUMBIA.

ATTACHMENT FOR BOOK TYPE-WRITERS.

SPECIFICATION forming part of Letters Patent No. 651,766, dated June 12, 1900.

Application filed March 10, 1900. Serial No. 8,168. (No model.)

To all whom it may concern:

Be it known that I, JULIA K. McDANIEL, residing at Washington, in the District of Columbia, have made certain new and useful Improvements in Attachments for Book Type-Writers, of which the following is a specification.

My invention is an attachment for book type-writers, designed especially for use in connection with type-writers of the class employing a hinged platen which is adjustable vertically at its free end, which class of type-writers is well represented by that known as the "Elliott & Hatch."

15 My invention has for an object to provide means for adjustably supporting the free end of the platen, whereby it may be secured and supported at any desired height; and the invention consists in certain novel constructions and combinations of parts, as will be hereinafter described and claimed.

In the drawings, Figure 1 is a perspective view of my invention as in use. Fig. 2 is a vertical longitudinal section. Fig. 3 is a face 25 view of the improvement, and Fig. 4 is a detail section illustrating the clamp for the link-bars.

The type-writer shown is of the type generally known as the "Elliott & Hatch" book 30 type-writer, including the platen A, which is hinged at A' and has its opposite or free end adjustable vertically by swinging upon the hinge A'. The hinged end A' is also adjustable vertically, this vertical adjustment permitting the adaptation of the platen to any 35 pages of a book.

By my invention I support the free end of the platen by means operating at or immediately adjacent to such end of the platen, so 40 the space beneath the platen will be unobstructed. By this means the back of the book may lie beneath the platen and upon the stand in the use of the invention. This construction also permits the shifting of the book 45 from side to side beneath the platen and avoids the lifting of the platen when it is desired to shift the book to write on one or the other side of the leaf in the operation of the type-writer.

50 In carrying out my invention I provide what for convenience of reference I term a "carrier," on which is mounted the vertically-

adjustable supporting device for the free end of the platen. This carrier is preferably adjustable longitudinally in suitable guides so 55 it can be set with respect to the type-writer to adapt the support for books of different lengths, and in the specific construction shown the carrier consists of slides B and B' in the form of bars which are held and movable longitudinally in guides C, secured to the stand D, on which the type-writing machine is supported. The guides C are preferably secured to the under side of the stand D, so they will not offer any obstruction to the free shifting 60 of the book beneath the platen, as before described.

It is manifest that by means of the guides C the carrier may be readily adjusted with respect to the stand in the use of the device 70 and can be conveniently removed from and applied to the stand whenever desired.

The carrier supports the vertically-adjustable devices for supporting the free end of the platen. As shown in the accompanying 75 drawings, these adjustable supporting devices comprise link-bars E and F, which are jointed at their ends E' and F' to the slides B and B', cross each other between their ends, where they are connected by an adjustable 80 clamp, and support at their upper ends a top bar G, which underlies the free end of the platen and is preferably made in the angle form shown, thus providing a flange G', which is pivoted at G² to the upper end of the bar 85 F and is provided with a series of notches G³ to receive a suitable stud or portion E² at the upper end of the link-bar E.

Slots e and f are formed longitudinally in the bars E and F for the play of the screw 90 H', forming a part of the clamp H. The screw H' has a head H², which fits in a longitudinal rabbet e', formed on the inner side of the bar E, so the screw will be held from turning in all its adjustments, and the winged 95 nut H³ may be operated to clamp the bars E and F tightly together in any desired adjustment.

It is manifest that by raising and lowering the upper ends of the bars E and F and engaging the stud E² in the proper one of the notches G³ the top bar G may be set to any desired position to properly support the platen. It will be noticed that the notches G³ are in-

clined slightly and that when the stud E² is held in one of said notches and the clamp H is tightened the bar G will be locked in engagement with said stud and cannot be accidentally displaced.

In the operation of my invention the bar G may be adjusted, as before described, to secure the platen at the desired height, and the leaf which it is desired to write upon be 10 supported upon the platen, while the back of the book underlying said leaf may rest beneath the platen and upon the stand. The stand may be a table, as shown, or any other suitable form of supporting-stand adapted 15 to carry the type-writer and the platen-supporting devices, as before described.

Having thus described my invention, what I claim, and desire to secure by Letters Patent, is—

- 20 1. A support for the platen of a type-writer, comprising the link-bars crossing each other between their ends and slideable along each other at the crossing, means for securing the link-bars together at the crossing, the top bar carried by the link-bars, one of the latter being movable along the top bar in adjusting the support, and means for holding the said movable link-bar to the top bar in any desired adjustment, substantially as set forth.
- 25 2. The combination substantially as described, of the bars pivotally supported at their lower ends and crossing between their ends, the top bar jointed to the upper end of one of the bars and provided with a plurality of notches arranged for engagement by a portion at the upper end of the other bar, and a clamp connecting the bars at the crossing.
- 30 3. A support for the platen of a type-writer comprising the link-bars pivoted at their lower ends crossing each other between their

ends and having longitudinally-extended slots at the point of crossing, the clamp connecting said bars and including a screw passing through said slots, and the top bar pivoted to one of the link-bars and having a plurality 45 of notches arranged for engagement by a portion at the upper end of the other link-bar, said notches being inclined, substantially as set forth.

4. In an apparatus substantially as described, a table or like support having guides below its top, combined with the bars slideable longitudinally in said guides, and the vertically-adjustable platen-support carried by said bars, substantially as set forth. 50

5. In an apparatus for supporting the platen of a type-writer, the combination of the carrier, guides in which said carrier is movable longitudinally, and a vertically-adjustable device on said carrier adapted to form a rest 55 for the platen.

6. An apparatus for supporting the platen of a type-writer comprising a carrier consisting of slide-bars, guides in which the same are movable longitudinally, and the vertically-adjustable devices on such carrier and adapted 60 to form a rest for the platen.

7. An apparatus for supporting the platen of a type-writer, comprising a carrier, link-bars jointed at their lower ends thereto, fixed relatively at such ends as to lateral movement, and crossing between their ends, and a top bar carried by the upper ends of the link-bars, one of said link-bars being adjustable 70 along the top bar.
